[57] CLAIM

The ornamental design for a hand-held pipetting device,
as shown and described.

DESCRIPTION

FIG. 1 is a top plan view of a hand-held pipetting device,
showing our new design;

FIG. 2 is a side elevational view, the opposite side being
a mirror image thereof;

FIG. 3 is a front elevational view thereof;

FIG. 4 is a rear elevational view thereof;

FIG. 5 is a bottom plan view thereof.

FIG. 1

FIG. 2

FIG. 3

FIG. 4

FIG. 5
